PUMP OR THE LIKE

Chester R. McFarland, Hightstown, N.J., assignor, by
mesne assignments, to De Laval Turbine Inc., Trenton,
N.J., a corporation of Delaware

Filed Nov. 21, 1960, Ser. No. 70,476

1 Claim. (Cl. 103—108)

This invention relates to pumps, compressors, or the like, and has particular reference to such machines having multiple stages and of the so-called "barrel" type.

Reference will be particularly made to liquid centrifugal pumps of the type involving delivery of liquid at high pressure. For this purpose, there are commonly provided pumps of the barrel type in which rotary impellers carried by a common shaft are assembled with a casing made up of disc-like stage elements which are stacked together. This assembly is then located in an outer housing capable of withstanding the pressure gradients, the stacked elements being held together primarily by the pressure gradient between outlet and inlet. This construction is in contrast with centrifugal pumps in which all of the passage-defining parts, or the majority of them, are provided in the halves of a casing split axially.

In the case of barrel pumps a manufacturer is frequently called upon to meet specifications for deliveries and pressures which call for various numbers of stages and different size impellers, but which specifications may be met by casings of the same diameter. It is a general object of the present invention to provide a pump construction requiring, for a single pump, duplicate parts, and for pumps for different capacities and delivery pressures parts which may be similar except for minor dimensional differences readily achieved by machining of castings. In brief, the invention contemplates the provision of a wide variety of pumps producible from the same interstage diaphragms and diffuser assemblies merely by simple turning of standard castings. While the invention is particularly applicable to pumps presenting the variable problems indicated above, it will become evident that the invention is also applicable to centrifugal compressors, turbines, or the like.

The foregoing general object as well as subsidiary objects relating to details of construction and arrangement will become apparent from the following description read in conjunction with the accompanying drawings in which:

FIGURE 1 is an axial section showing the pertinent parts of a pump constructed in accordance with the invention;

FIGURE 2 is an elevation of a diffuser element located between the discharge of one impeller and the entrance to a subsequent one;

FIGURE 3 is an elevation looking at the right-hand side of FIGURE 2;

FIGURES 4 and 5 are diagrams illustrating the assemblies of interstage diaphragms provided in accordance with the invention; and

FIGURE 6 is a diagram illustrating the form taken by a standard casting from which interstage diaphragms may be readily produced by machining.

Referring first to FIGURE 1, the pump shown is of the barrel type, and except for the parts specially provided in accordance with the invention has a generally conventional structure and operates in conventional fashion. An outer housing 2 is provided having a generally cylindrical form and designed to withstand the pressures involved. This housing is provided with an inlet passage at 4 and a discharge passage at 6. The housing is provided at its left-hand end with a shoulder 7 against which the casing assembly abuts under the high discharge pressure. At its right-hand end the housing is provided with

2

a conventional closure 8, which houses conventional packing and bearing arrangements which are not illustrated. At the left-hand end of the housing there is the bearing assembly generally indicated at 10. The invention is concerned primarily with the barrel assembly within the housing and details of the housing and other structures are not involved and are therefore not shown in detail. It need only be remarked that for pumps of different lengths (i.e. different numbers of stages) different housing 2 will be provided, though the associated end closures, bearings, etc., may be standard for different size pumps.

The casing which is located within the housing is made up of stacked elements comprising the end element 12, the duplicate interstage diaphragms 14, and the outlet element 16. Concentric stacked arrangement of these elements is maintained by interlocking rabbets as will be evident from FIGURE 1. Nested in the interstage diaphragms 14 are diffuser elements 18 secured by bolts 19. A shaft 20 has mounted thereon in conventional fashion the various impellers 22 of the stages involved, these being provided with the usual vanes. For pumps of different capacities these impellers will, in general, be different in the sense of having wider or narrower passages between the vanes; but in any individual multi-stage pump the impellers will generally be identical in usual pumps. In the case of pumps of different capacities, despite the differences of the impeller passages the impellers will usually be the same in their structural relationship to the shaft and the interstage dimensions will be the same. Consequently, the same shaft may be used for pumps to the same number of stages but of different capacities, assuming, of course, that radial dimensions involved are substantially the same. While the generally very high pressure drop between outlet and inlet will maintain the assembly, it is desirable in the assembly operation to hold the interstage diaphragms together in final stacked relationship, and for this purpose tie elements 24 are used as described in the application to Karol Pilarczyk, Serial No. 130,988, filed August 11, 1961.

Considering the already described aspects of duplications of parts for pumps to different capacities and numbers of stages, the invention provides simplification in the matter of minimizing the variety of elements to be used by special forms and assemblies particularly of the interstage diaphragms and the diffuser assemblies or elements.

The type of diffuser element provided in accordance with the invention is illustrated in greater detail in FIGURES 2 and 3. This diffuser element 18 comprises a cast disc which is of small axial extent except at its peripheral portions. It comprises diffuser vanes on the side facing the discharge of one impeller, cross-over passages for the liquid being pumped, and return passages and guide vanes on its opposite side arranged to direct the flow to the inlet of the next subsequent stage impeller. The relatively thin central portion of this element is indicated at 21. Adjacent the periphery there are provided the diffuser vanes 23 which spiral outwardly from their inlet edges 25. On the opposite side of the disc there are the return vanes 27 which spiral inwardly from their inlet edges at 26 to their outlet edges at 28. As will be evident from FIGURE 3, in particular, cross-over passages 30 exist at the periphery of the element 18 to carry the liquid from one side to the other of the central portion 21. Closer to the shaft there are provided the redirecting vanes 36 to turn the inwardly spiraling flow substantially radially for entrance into the eye of the next stage impeller without substantial spin.

Consideration of the construction just described will

reveal that starting with an ample width between the generally radial faces 32 and 34 of this construction a simple turning procedure carried out on a lathe may be used to form diffuser elements of different widths as to both entrance and exit passages. As will become clearer from the following consideration of the interstage diaphragms, this results in extreme ease of adaption of a single standard type of casting to produce the diffuser elements for pumps of different capacities, in particular to fit them to impellers of different sizes.

Reference may now be made to FIGURES 4 and 5 showing the assembly arrangement of interstage diaphragms, two adjacent ones of which are illustrated. In the arrangement illustrated in FIGURE 4, these diaphragms are arranged to provide a minimum of axial space for the diffuser elements, the space 40 having the typical dimension A_1 . (The space, as indicated, may involve both radial and conical wall portions; but the dimension A_1 may be regarded as typical). Still referring to FIGURE 4, a typical wall thickness dimension is indicated at B_1 . From the fact that these typical dimensions are taken between radial wall portions, it will be evident that the interstage dimension, i.e. the space of similar parts of the impellers and the other repetitive elements will be A_1+B_1 .

On the other hand, considering FIGURE 5, the space 40' is here indicated as the maximum space that may be desired in the case of a larger capacity impeller with a correspondingly axially wider diffuser element. The space dimension A_2 is now greater. The wall dimension B_2 for the interstage diaphragms is now such that A_2+B_2 is equal to A_1+B_1 . The interstage spacing is thus constant.

Considering, now, FIGURE 6, the outside outline of this indicates the shape of a casting 14A from which both the extreme size diaphragms 14 and 14' may be produced by simple turning. To provide a diaphragm such as 14 of maximum wall thickness the shaded portion 42 may be removed. On the other hand to produce the diaphragm of minimum wall thickness the shaded portion 44 may be removed. It will also be obvious that from this same casting 14A machining may produce any diaphragm of intermediate wall thickness by partial removals of material at both the right and left. (The original casting may, of course, be provided with excess material such as indicated at 46 to provide for proper finish machining.)

As will now be evident, the amply sized casting 14A and a casting for the diffuser element having an ample dimension between the faces 32 and 34 will suffice for the construction and assemblage of pumps having different size impellers and/or different numbers of stages. When the proper machining is accomplished to remove excess material, the diffuser elements will rest within and may be secured in the cups formed within the interstage diaphragms, securing being achieved by bolts as indicated at 19. The stacking of the interstage diaphragms will then result in the establishment of standard spacing for the various repetitive elements, including the impellers, along the shaft. The result is a completely satisfactory construction from the standpoint of operation with greatly simplified aspects of production of parts and their stock piling to meet the demands of various orders for pumps.

It will be evident from the foregoing that the invention is equally applicable to other rotary machines such as compressors and turbines. In the case of compressors the successive stage impellers are generally of

5 different size; and in such case, of course, the interstage diaphragms and the diffuser elements may also successively change in size from stage to stage. But in accordance with the invention these latter elements may also be machined, by turning, from the same standard castings.

10 In the case of turbines of gas or liquid types, discs similar to the diffuser elements of the pumps will carry vanes on one or both sides to define diffusers (which may, of course, be vaneless) and nozzles as well as redirecting vanes, all to provide gas or liquid passages functioning conventionally but structurally having the advantages of the invention.

15 It will, therefore, be clear that various changes may be made in accordance with the invention, adapting it to different rotary fluid handling devices, without departing from the scope thereof as defined in the following claim.

What is claimed is:

20 A multistage pump or the like comprising a rotary shaft, axially spaced vaned rotors carried by the shaft, a housing for said shaft and rotors, said housing comprising coaxially stacked peripherally abutting interstage diaphragms, one for each rotor, each of integral, vaneless and cup-shaped form, i.e., having a radially directed portion through which said shaft extends centrally and an outer peripheral portion projecting therefrom at one side of said radially directed portion, and disc-shaped elements in the spaces within each of said respective cup-shaped diaphragms, each of said elements comprising a radial portion, diffuser vanes integral with said radial portion, extending axially from said radial portion in one direction and spiralling outwardly, return vanes integral with said radial portion, extending axially from said radial portion in the opposite direction and spiralling inwardly, and redirecting vanes integral with said radial portion extending axially from said radial portion in the last mentioned direction and spiralling inwardly, said elements providing helical cross-over passages between said diffuser vanes and return vanes, and each of said 25 elements having all of its respective vanes terminating axially substantially at the radially directed portions of said diaphragms, and each of said elements presenting outwardly extended cylindrical portions between said cross-over passages, all of said diaphragms having substantially identical radial extents of their parts, and all of said elements having substantially identical radial extents of their parts, with said diaphragms and elements alone defining the flow passages from each rotor to that of the next succeeding stage, and a casing surrounding the diaphragms and separated from said elements by said stacked diaphragms.
